Primary Examiner—Caron Veynar*Assistant Examiner*—Ricky Pham(74) *Attorney, Agent, or Firm*—Pearne & Gordon LLP(57) **CLAIM**

The ornamental design for a blender jar, as shown and described.

DESCRIPTION

FIG. 1 is a perspective view of a blender jar showing our new invention;

FIG. 2 is a top view thereof;

FIG. 3 is a right side view thereof;

FIG. 4 is a front view thereof;

FIG. 5 is a left side view thereof; and,

FIG. 6 is a bottom view thereof.

The stippling shown in FIGS. 1-4 and 6 is provided to illustrate the contrast between a portion of the surface of the handle and the adjacent surfaces, and does not represent any particular surface treatment.
